William Brown, Sr., Scarsdale, N. Y., assignor to The
Buxbaum Company, Canton, Ohio, a corporation of
Ohio

Application February 21, 1955, Serial No. 34,611

Term of patent 14 years

(Cl. D92—4)

Fig. 1

Fig. 2

Fig. 1 is a plan view of a rubber floor covering showing my new design; and

Fig. 2 is an enlarged fragmentary view of the floor covering shown in Fig. 1 illustrating a portion thereof at a 90° angle thereto.

The floor covering is of conventional thickness.

A unit is enclosed in broken lines in the drawing and is repeated as indicated.

I claim:

The ornamental design for a rubber floor covering or similar article, substantially as shown and described.
